UNITED STATES PATENT OFFICE.

WILLIAM G. ARROWOOD, OF HAWTHORNE, CALIFORNIA.

INCINERATOR.

Application filed November 13, 1923. Serial No. 674,535.

To all whom it may concern:

Be it known that I, WILLIAM G. ARROWOOD, a citizen of the United States, residing at Hawthorne, in the county of Los Angeles and State of California, have invented new and useful Improvements in Incinerators, of which the following is a specification.

The present invention relates to improvements in incinerators, and particularly to apparatus of this character which is intended primarily for safely burning garden or lawn trash or rubbish or household waste materials.

An object of the invention is to provide a durable device or apparatus for the purpose described, which shall be relatively inexpensive of manufacture whose parts may, if desired, be readily separated or assembled.

With this and other objects in view, the invention resides in the construction and arrangement of parts that will be hereinafter more particularly described and pointed out in connection with the accompanying drawing.

It will be understood that in the drawing some of the parts are shown more or less conventionally, and that unless specifically included in the appended claims, the invention is not intended to be limited to the exact details illustrated, the drawing being designed to be illustrative rather than restrictive of the invention.

In the drawing:—

Figure 1 is an elevation of an incinerator constructed in accordance with the present invention.

Figure 2 is a vertical section substantially on the line 2—2 of Figure 1.

Figure 3 is a horizontal section substantially on the line 3—3 of Figure 1.

Figure 4 is a detail perspective view of a portion of one of the corner pieces or uprights and of two of the metal elements of the incinerator walls.

Referring to the drawing, it will be seen that the embodiment of the invention illustrated is composed of four uprights or corner pieces 1, walls connecting said corner pieces and formed of a plurality of courses of brick or tile 2 separated by metal bars 3, and a top 4, which embraces the upper ends of the walls and corner pieces or posts.

The metal corner pieces or uprights 1 are 55 of such form in cross section that each of them will embrace the adjacent ends of two of the side walls, and, as above stated, all of said corner pieces and the walls are held together by the top or cap piece 4. 60

To insure stability of the apparatus, spur pieces or anchors 5 may be provided, which will be embedded in the ground with their upper ends extending into the lower ends of the uprights or posts 1. 65

As shown, each corner piece or upright is formed from a sheet metal blank, which is folded upon itself to provide two longitudinal channels 6, 7, arranged at right angles to each other and the ends of the side walls 70 extend into these channels.

Each side wall is preferably composed of a plurality of courses of brick or tile, the term "brick" being hereinafter employed as descriptive of blocks, slabs or plates of 75 any suitable fireproof material. The bricks 2 may be of any desired size.

The metal bars 3, which separate the several courses of brick in each side wall, are made of channel form in cross section, and 80 the flanges 9 thereof extend over the opposite faces of one of the courses separated by the bars.

In the particular embodiment illustrated, the separating bars 3 are arranged with 85 their channel faces upward, so that the lower edges of the bricks 2 are fitted snugly therein.

Referring to the drawings it will be seen that the lower tier of brick include members 90 11 extending parallel to opposite sides of the incinerator body and forming passages 10, which extend throughout the width of the apparatus and are open at both ends. The passages 10 thus formed provide a 95 ready means for removal of ashes and the upper edges of the walls 11 of such passages serve as supports for the material being burned.

The outer side walls of the passages 10 are 100 supported, as shown, by two of the separating bars 3.

In one of the side walls, the bricks are so arranged as to leave an opening 12, through which the contents of the apparatus may 105 be ignited.

The top 4 is preferably made of metal, and has a marginal flat base section resting

on the top of the side walls and having depending marginal flanges 13, which closely embrace the sides of the walls and the uprights 1. Said top is provided with a smoke outlet 14, about which may be fitted a suitable stack 15, and one wall of the top is inclined from the outlet 14 forward to the portion 16 which rests upon the upper ends of the walls. In this inclined section of the top 10 is formed an opening which is closed by a door or cover 17 pivotally mounted or hinged to a suitable frame as at 18. As shown the opening in the top is provided at opposite sides with outwardly projecting members 20 and the cover 17 has an outwardly projecting marginal flange 21. The pivot rod 18 extends through the frame members 20 and adjacent sections of the marginal door flange 21. The lower, transversely extending, section of the door flange is adapted to extend parallel to the section 16 of the top 4 when the door is in open position. The opening adapted to be closed by the door 17 serves as a means for introducing into the apparatus the material to be burned, and it will be noted that when the door is opened or turned into the position represented in dotted lines in Figure 2, it constitutes a guide, or side wall of a hopper which will act to guide material deposited thereon into the interior of the apparatus.

A screen 19 is preferably placed across the smoke outlet 14 to prevent flaming particles from being carried out of the apparatus when in use.

It is believed that the operation and advantages of the apparatus will be evident from the foregoing description taken in connection with the drawing. The apparatus may, of course, be made in various sizes and of different forms. The parts thereof can be readily assembled in position for use, or, if desired, can be disconnected and stored in a minimum amount of space. The corner pieces and bars separating the brick of the side walls may be of relatively light metal and when the parts are assembled, a strong and durable apparatus is provided.

The side walls and corner pieces are securely interlocked when assembled, and there is no danger of fire escaping to damage articles outside of the apparatus when it is in use.

Having thus described the invention, what is claimed and desired to be secured by Letters Patent is:

1. An incinerator comprising metal corner pieces each provided with two longitudinal channels, walls connecting the corner pieces and each including a plurality of horizontal metal bars and bricks separated vertically by said bars, the ends of the bars and adjacent ends of the bricks extending into

aligned channels in the corner pieces, and a top embracing the upper ends of the corner pieces and walls and provided with an opening through which material may be deposited in the incinerator.

2. An incinerator comprising metal corner pieces having channels formed therein, walls connecting the corner pieces and each wall including a plurality of horizontal metal bars and suitable brick separated vertically by said bars, the ends of the bars and adjacent ends of the brick extending into aligned channels in the corner pieces, a top covering the space enclosed by the walls and provided with a smoke outlet and an inclined section having therein an opening through which material may be deposited in the apparatus, and a hinged closure for said opening adapted to be turned into a position at an angle to the inclined section of the top to form a guide for directing material to said opening.

3. An incinerator comprising side walls each including a plurality of courses of brick separated by horizontal metal bars of channel form in cross section, with the vertical flanges of each bar projecting over the faces of the brick in one of the courses separated thereby, metal uprights embracing adjacent corners of the side walls, and a top embracing the upper ends of the side walls and the corner pieces.

4. An incinerator comprising side walls each including a plurality of courses of brick separated by horizontal metal bars of channel form in cross section, with the vertical flanges of each bar projecting over the faces of the brick in one of the courses separated thereby, metal uprights each provided with two vertical channels arranged at an angle to each other, the sides of each wall extending into aligned channels in said uprights, and a top covering the space enclosed by the walls and uprights.

5. An incinerator comprising side walls each including a plurality of courses of brick separated by horizontal metal bars of channel form in cross section, with the vertical flanges of each bar projecting over the faces of the brick in one of the courses separated thereby, metal uprights each provided with two vertical channels arranged at an angle to each other, the sides of each wall extending into aligned channels in said uprights, and a metal top embracing the upper ends of the walls and uprights and provided with a smoke outlet.

6. An incinerator comprising side walls each including a plurality of courses of brick separated by horizontal metal bars of channel form in cross section, with the vertical flanges of each bar projecting over the faces of the brick in one of the courses separated thereby, uprights, each formed from a sheet metal blank bent upon itself to

provide two longitudinally extending channels arranged at an angle to each other, engaging the adjacent edges of adjacent side walls, and a top covering the space enclosed by the walls and uprights.

7. An incinerator comprising side walls each including a plurality of courses of brick, metal uprights or corner pieces having channels embracing the adjacent edges 10 of the side walls, a top, and an anchoring spur cooperating with each corner piece having its body extending upward into a channel in the upright.

8. An incinerator comprising channel 15 formed corner uprights, side walls having their ends within the channels in the uprights, and a top telescopically fitted about the upper ends of the walls and uprights and maintaining them in engagement and provided with an aperture through which material may be introduced into the incinerator.

9. An incinerator comprising side walls each including a plurality of courses of brick, 25 metal uprights having grooves receiving the ends of the side walls, a top closely embracing the side walls and uprights and provided with an aperture through which material may be introduced into the incinera-

tor, and a movable closure for said aperture in the top.

10. An incinerator having side walls of refractory material, uprights or corner pieces each having two vertical channels extending at an angle to each other and receiving the adjacent ends of the side walls, and a top embracing the upper ends of the walls and uprights.

11. An incinerator comprising corner pieces, each provided with two vertical channels, having parallel vertical sides, walls connecting the corner pieces and having their ends fitting in said channels, and a cover extending over the space inclosed by the walls and corner pieces.

12. An incinerator comprising vertically channelled corner pieces; walls connecting the corner pieces and having their ends fitting in channels therein, a cover for the space inclosed by the walls having a base 50 surrounding the upper ends of the walls and an aperture through which material may be introduced into the incinerator, and a movable closure for said aperture.

In testimony whereof I have hereunto set 55 my hand.

WILLIAM G. ARROWOOD.
